UNITED STATES PATENT OFFICE.

MICHAEL LICHTMAN, OF NEW YORK, N. Y.

TELESCOPE.

Application filed December 15, 1920. Serial No. 430,619.

To all whom it may concern:

Be it known that I, MICHAEL LICHTMAN, a citizen of the United States, and a resident of the city of New York, borough of Manhattan, in the county and State of New York, have invented a new and Improved Telescope, of which the following is a full, clear, and exact description.

This invention relates to a telescope and 10 has for an object to provide a telescope structure which is simple and compact and economical to manufacture.

Another object of the invention resides in the provision of means whereby the plurality of telescoping sections can be fitted and constructed to slide with respect to one another by the use of a minimum number of parts in the construction, which greatly enhances the simplicity of the device.

20 A further object resides in the particular construction and arrangements of parts hereinafter described and claimed and shown in the accompanying drawings.

The invention is illustrated in the drawings, of which—

Figure 1 is a longitudinal section taken on the line 1—1 of Figure 2.

Figure 2 is a section taken on the line 2—2 of Figure 1.

30 As shown in the figures the invention comprises a telescope having an outer telescopic section 10 which is preferably made of some thin light metal, such as aluminum, covered by a layer 11 of some material such as leather, when desired. The outer end of this section 10 is adapted to receive a ring plug 12 against the end of which a lens 13 is placed. This lens is held in position by a clamping ring 14.

40 The other end of the telescoping section 10 is provided with an inwardly turned flange portion 15 adapted to form a bearing surface for the outer face of an inner telescoping section 16 which is made of material

similar to the section 10. One end of the 45 inner section 16 is provided with a cap portion 17 in which a lens 18 may be mounted in connection with a retaining ring 19 in a manner well known in the art. The other end of the inner section 16 is provided with 50 an outwardly extending flange portion 20 which is adapted along its outer edge to lie parallel and contact with the inner surface of the outer telescoping section 10.

It will be seen that as the inner section is 55 pulled out of and pushed into the outer section 10, the flange portion 20 slides along the inner surface of the section 10 which forms a bearing therefor, whereas the flange portion 15 of the outer section contacts with 60 and forms a bearing portion for the outer surface of the inner section 16. By this construction these two sections can slide with respect to each other and are kept in alignment in a simple and efficient manner. This 65 alignment construction can be made by merely pressing the sheet metal of the telescope section into the proper shape. This sort of manufacture results in an article 70 which can be very economically manufactured, and at the same time compact and efficient in its operation.

I claim:

A telescope comprising inner and outer telescoping sections formed of stamped 75 metal, an off-set flange of larger diameter formed on one end of the inner section and bent parallel to the inner surface of the outer section, said flange having a substantial length to form a bearing surface, and a 80 ringlike flange of smaller diameter on the opposite end of the outer section to form the bearing for the inner section, the said second flange bent parallel to the outer surface of the inner section and having a substantial length to form said bearing.

MICHAEL LICHTMAN.
